LAUNDRY MARKER COUNTER

Angus F. Hanney, Norwood, Ohio, assignor to
The American Laundry Machinery Company,
Cincinnati, Ohio, a corporation of Ohio

Application February 7, 1930, Serial No. 426,614

5 Claims. (Cl. 235—128)

My invention relates to a counter mechanism. It pertains, particularly, to a device for calculating and determining the number of marking clips on a clip key bar and is particularly adapted for use in laundries where such marking clips are used.

In laundries, it is a general practice to attach a clip on each piece of goods belonging to any one person before the goods are sent through the laundering processes. It is then customary to detach such identifying clips from the goods after they have been laundered and before sending them to their respective destinations. In this manner an accurate check is kept on the number of pieces in any one group of pieces that have been laundered. Therefore, it is important that some means be provided for making an accurate check on the number of clips used prior to the laundering process and on the number of clips removed from the pieces in any one group after laundering to determine whether or not all of the goods in any one group are accounted for. In such a system it has been the practice to provide a single or a number of clip key bars for each separate bundle of goods to be laundered, the key bars having the same number of marking clips thereon and that number being constant.

Heretofore, the calculating or counting of clips on the key bars prior to the attachment of the clips to the goods and after the removal therefrom has been done by hand or by some more or less inefficient and relatively inaccurate device. Further, the counting of these clips consumed a large amount of time.

One object of my invention is to provide a device for accurately and quickly registering or counting the number of clips on a clip key bar.

Another object of my invention is to provide a device for calculating or counting the number of marking clips on a clip key bar of such nature that the registering device will automatically reset itself to normal zero position after the clips on the key bar have been counted.

Still another object of my invention is to provide a device of such nature that each clip will be accurately registered and to provide an audible signal which will indicate whether or not the desired number of marking clips on each key bar are present.

Other objects and various advantageous features of my invention may be seen in the following detailed description, and one embodiment thereof may be seen in the accompanying drawing wherein similar characters of reference designate corresponding parts and wherein Fig. 1

is a view showing the preferred embodiment of my invention.

Fig. 2 is a view similar to Fig. 1 but showing the parts in different operative position.

Fig. 3 is a side elevation of the device shown in Figs. 1 and 2.

Referring to the drawing, I have shown one embodiment of my invention as comprising a plate 1 forming the main frame of the device and provided with a rectangular trough-like guide 2 at its lower edge which is adapted to receive a clip key bar 3 having marking clips 4 mounted thereon. As shown, a disc or wheel 5 is mounted for rotation on a post 6 extending outwardly from the main frame 1, and a spiral spring 7 having one of its ends attached to the disc or wheel 5, as at 8, and its opposing end attached to the frame 1, as at 9, is disposed between the inner face of the disc or wheel 5 and the corresponding face of the frame 1 to yieldably resist rotation of the disc or wheel 5 in a clockwise direction Fig. 1, and to maintain the disc or wheel in such position that a lug 10 thereon normally abuts against a stop 11 provided on the frame. This arrangement normally resists movement of the disc or wheel 5 in a clockwise direction and returns the disc or wheel to its normal starting position after it has been rotated.

The disc or wheel 5 has a series of notches 12 about its outer circumference and these notches are preferably the same in number as the number of marking clips ordinarily supposed to be disposed on the clip key bar 3. The spacing of the notches 12 is substantially the same as the spacing of the tops of the clips 4 when nested closely together on the key bar 3. A lever or bell crank 13 is pivoted to the frame 1 as at 14, and so disposed that one end thereof will normally abut against the post 6 which acts as a stop therefor. A spring 15 is connected at one of its ends to that same end of the lever or bell crank 13 and at its other end to some convenient place on the frame 1, in this instance to an arm 16 extending outwardly from the frame. This spring tends to hold the lever or bell crank in the position shown. A rod or wire 17 is rigidly secured to the same end of the lever or bell crank 13 and has a ball 18 on its extreme outer end. A bell or gong 19 is provided against which this ball 18 is adapted to strike under certain conditions to produce an audible signal.

The outer face of the disc or wheel 5 has an operating member 20 loosely pivoted thereon as at 21 and normally held in the position shown in Fig. 1 by means of a spring 22 that is connected

at one end to the member 20 and at its opposing end to the face of the disc or wheel 5. That is, the spring member 22 is normally adapted to hold the member 20 in its lowermost position and against a stop 23 provided on the face of the disc or wheel 5 and operating within a slot 24 in the member 20. The member 20 is pivoted adjacent the last notch 12 on the outer circumference of the disc or wheel and one end of such member 10 is coincident with such last notch.

In the operation of this device the key bar 3, having the marking clips 4 thereon and abutting against a stop 30 on the key bar provided for that purpose and against each other in the manner 15 shown, is inserted into the rectangular guide 2 as in Fig. 1. Pressure is exerted on the key bar to move it through such guide way and, after the key bar moves a given distance, the top of the first marking clip will contact with the radially 20 extending lug 10, whereupon continued movement of the key bar through the guide way will rotate the disc or wheel 5 on its pivot post 6 against the resistance of the spring 7 hereinbefore described.

25 After initiation of such rotation of the disc or wheel 5 by contact of the radially extending lug 10 with the top of the first marking clip, the tops of the remaining clips are engaged by the notches 12 about the outer circumference of the wheel 30 or disc and, since the spacing of the notches is substantially the same as the spacing of the tops of the marking clips, each succeeding clip will be engaged by each succeeding notch on the outer circumference of the disc or wheel. By suitably numbering the notches 12, the number of clips carried by the key bar 3 up to any given point within its length may be accurately determined.

However, it is customary to have a definite 40 number of clips on each key bar. Therefore, I have provided a means for indicating to the operator when the desired number of clips, in this instance fifty, are on the key bar.

As the rotation of the disc or wheel 5 is continued by the engagement of successive clips with successive notches on the disc or wheel, the disc or wheel will eventually reach such position, after almost a full revolution of the disc or wheel, that the last notch will be in contact with the top of 50 the last clip on the key bar, as shown in Fig. 2. When such last notch is reached, the part of the member 20, which coincides with the last notch on the disc or wheel, will contact with the top of the last clip and continued movement of the disc 55 or wheel will bring a projection 25 on the member 20 into contact with the lowermost end 26 of the bell crank or lever 13 by moving the member 20 upwardly; then, continued rotation of the disc or wheel 5 will move the lever or bell crank 13 about its pivot, as shown in this figure, and away from the post 6 which normally acts as a stop. Further, such movement will be against the tension of the spring 15 and as the disc or wheel continues its movement by reason of movement 60 of the key bar 3 through the guide 2 the projection 25 will ultimately move out of contact with the lowermost end 26 of the lever or bell crank 13. When so released, the lever or bell crank 13 will be moved back against the stop 6 by the 70 spring 15 in such manner that the ball 18 will strike against the gong 19 and produce an audible signal. Thus, I have provided a means for informing an operator when a key bar contains the desired or full number of marking clips. Less 75 than the desired full number of clips on a bar will

result in the signal not sounding as will be apparent since the member 20 will not contact with a clip and be moved.

Should there be more clips on the key bar than there are notches in the disc or wheel, it will be 5 readily seen that the additional clip will jam between the part of the periphery of the disc or wheel on which there is no notches and the key bar and the device will not function.

The particular marker used with the apparatus 10 described by this invention comprises a clip made of some resilient metal that is bent into substantially the shape of a U with the free ends pressed together, the goods being gripped between the free ends of such clip when the clips 15 are attached thereto. One leg of this U shaped clip is preferably made wider than the other leg and is made with a key perforation adapted to fit upon the key bar 3. However, any desired type of clip might be used.

20 Referring to the drawing and the preceding description it will be apparent that I have provided a device for counting the number of marking clips on a key bar embodying numerous novel and advantageous features. For instance, I have 25 provided a device by means of which the number of clips on a key bar will be quickly and accurately determined and an audible signal will be sounded after the desired number are on such key bar, with no signal being sounded if less 30 than the desired number are thereon. However, my device is such that, should there not be the desired number of clips on the key bar it would only be necessary to pass the key bar through the device and stop movement of the key 35 bar when the last clip thereon is in engagement with its corresponding notch to quickly and accurately determine the number of clips on the key bar.

What I claim is:

40 1. Apparatus of the class described, comprising a supporting device adapted to hold a plurality of clips in definite order or arrangement, and means adapted to receive said supporting device with the clips thereon and provided with 45 means arranged to produce an indication to the operator when a predetermined number and no other number of clips are on the supporting device, said last named means including a device adapted for operation by the last one of a pre- 50 determined number of clips held in said device.

2. A counter mechanism for laundry marking clips comprising, in combination, a supporting device adapted to hold a plurality of clips in definite order or arrangement, and means adapted 55 to receive said supporting device with the clips thereon and provided with means arranged to produce an indication when a predetermined number of clips and no other number are on the supporting device, said first named means including a frame and a guideway in said frame adapted to receive said clip supporting device, said second named means including a rotatable element carried by said frame and adapted to be 60 actuated by movement of the clip laden supporting device along said guideway.

3. A counter mechanism for laundry marking clips comprising, in combination, a supporting device adapted to hold a plurality of clips in 70 definite order or arrangement, and means adapted to receive said supporting device with the clips thereon, said means being provided with means arranged to produce an indication to the operator when a predetermined number and 75

- no other number of clips are on the supporting device.
4. In a counter mechanism for laundry clips having an element rotatable by contact with clips assembled on a supporting device and including indicia on said element for indicating any number of clips within the capacity of said device, the combination of a frame supporting the rotatable element, said frame having a guideway for directing said device in a path adjacent said element, portions of said element being adapted to coact with clips on said device to rotate the element as the device is moved through the guideway, and means arranged to produce an indication when a predetermined number only of clips are on the supporting device.

5. Apparatus of the character described, comprising a frame, a clip-supporting device adapted to be moved therealong, a rotatable element carried by said frame and rotatable by the clips on said device during such movement thereof, 5 said element being provided with a predetermined number of circumferentially distributed, clip-receiving notches which limit the rotation of said element to that imparted to it by a corresponding number of clips on said device, signal 10 producing means, and means associated with the last notch of said element and operable by the clip cooperable therewith for controlling said signal producing means.
